UNITED STATES PATENT OFFICE.

JEFF HILL, OF FREEPORT, PENNSYLVANIA.

CAR-COUPING.

SPECIFICATION forming part of Letters Patent No. 359,075, dated March 8, 1887.

Application filed January 3, 1887. Serial No. 223,197. (No model.)

To all whom it may concern:

Be it known that I, JEFF HILL, a citizen of the United States, residing at Freeport, in the county of Armstrong and State of Pennsylvania, have invented certain new and useful Improvements in Car-Couplings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The invention will be first described in connection with the drawings, and then pointed out in the claims.

Figure 1 of the drawings is a top plan view of a car provided with my invention. Fig. 2 is a median vertical longitudinal section, and Fig. 3 a bottom plan view. Fig. 4 is a detail view of the draw-head.

In the drawings, A represents a car in whose bottom *a* is swiveled the hand-shaft B, which has one radial arm, *b*, above said bottom or platform, and another, *b'*, below it. These arms *b b'* are at an angle to each other, while the shaft may be turned from the top of car by a cross-bar or other suitable device, or from the sides by means of the lateral rods C C', which are attached to the outer end of the arm *b*.

D D are two vertical parallel boards, bars, or plates secured to the under side of the car, and between these is attached the draw-head E. This draw-head is made of a single piece of metal or wood, with two parallel arms, *e e*, the narrow slot *e'*, and the wide slot *e''*, together with the shoulders *e' e''*, one on each arm. This is a very simple construction, very strong, and very durable. Nevertheless its cost is small.

I place two cross-bolts, one passing across

each of the slots *e' e''* to hold the hook-coupler F between the arms *e e*, and on the front cross-bolt I pivot the two arms *g g*, of the kicker G, which has in front an upwardly-bent arm, 45 *g'*, squared at the end to support a link, H, pivoted to the hook F. The kicker G has also a rear arm, *g''*, which is connected by a pivoted rod, I, with the free end of the shaft-arm *b'*. By this construction and combination of 50 parts the kicker may be operated to hold the link H at the proper height for coupling, or may lift it still higher so as to make it uncouple, thus enabling said kicker to perform both the functions of coupling and uncoupling. A common link may be used, if desired.

I am aware that a hook has been attached between two bumpers to the cross-bar of the car-body and provided with a pivoted link; also, that a plate has been provided with two 60 arms to lift the link, so as to couple with an opposite draw-head, the arms clasping the sides of link; but this is a very different device, adapted to both couple and uncouple.

What I claim as new, and desire to protect 65 by Letters Patent, is—

1. The car-coupling kicker G, having the arms *g g*, straddling the hook F and pivoted thereto, the curved front arm, *g'*, end-squared to support the link, and the downwardly-bent 70 arm *g''* at the rear, as shown and described.

2. The hand-shaft B, having the arms *b b'*, the rods C C', the rod I, the hook F, and the kicker G, all combined and arranged as shown and described.

In testimony whereof I affix my signature in presence of two witnesses.

JEFF HILL.
